Specification for Design.

Patented Mar. 23, 1920.

Application filed October 27, 1919. Serial No. 333,854. Term of patent 14 years.

To all whom it may concern:

Be it known that we, ALFRED H. HUMPHREY and GEORGE A. HUMPHREY, citizens of the United States, and residents of the city of New York, county of New York, State of New York, (whose post-office address is 46 West Broadway, city of New York, county of New York, State of New York,) have invented a new, original and ornamental Design for Gas-Burners, of which the following is a specification, reference being had to the accompanying drawing, forming a part thereof.

Figure I is a side elevation and Fig. II is a plan view of a gas burner showing our new design.

We claim:

The ornamental design for a gas burner as shown.

ALFRED H. HUMPHREY,
GEO. A. HUMPHREY.
